UNITED STATES PATENT OFFICE

WILLIAM H. GESELL, OF MONTCLAIR, NEW JERSEY, ASSIGNOR TO A. S. HINDS CO., OF BLOOMFIELD, NEW JERSEY, A CORPORATION OF MAINE

DESIGN FOR A BOTTLE

Application filed July 14, 1932. Serial No. 44,328. Term of patent 14 years.

To all whom it may concern:

Be it known that I, WILLIAM H. GESELL, residing at Montclair, in the county of Essex and State of New Jersey, have invented a new, original, and ornamental Design for a Bottle, of which the following is a specification, reference being had to the accompanying drawing, forming part thereof.

Figure 1 is a front elevation of my new bottle;

Figure 2 is a side view thereof, and

Figure 3 is a bottom plan view thereof.

I claim:

The ornamental design for a bottle as shown.

WILLIAM H. GESELL.
